ELECTRON BEAM TUBE

George Ross Kilgore, Verona, N. J., assignor to
Radio Corporation of America, a corporation
of Delaware

Application June 27, 1940, Serial No. 342,625

15 Claims. (CL 250—175)

My invention relates to electron discharge devices, more particularly to such devices utilizing secondary emission electron multiplication.

Secondary emission multipliers of the voltage controlled type have offered a possibility of increasing the transconductance of amplifier tubes and more particularly the transconductance per unit capacity, which is recognized as the figure of merit for wide band amplification. However, in tubes of this type where conventional space charge control has been used in the input certain limiting factors are found. One is that the ratio of transconductance to plate current (g_m/I_p) is comparatively low. Now the current and transconductance increase together in the multiplier and the maximum current is limited by space charge or safe dissipation of the secondary emitting surfaces so that the maximum transconductance is limited by the g_m/I_p ratio. It is, therefore, desirable to obtain a control of the electrons entering the multiplier which allows a higher g_m/I_p ratio.

It can also be shown that the signal to noise ratio is a function of

$$\frac{g_m^2}{I_p}$$

so that by increasing

$$\frac{g_m}{I_p}$$

in the proper manner a lower noise tube may also be produced.

Further limiting factors in the conventional control are the high input loading at ultra high frequencies and the high capacities due to small electrode spacings.

It is, therefore, an object of my invention to provide an electron discharge device of the multiplier type having improved operating characteristics. More specifically it is an object of my invention to provide such a tube having comparatively high transconductance, low input and output capacities and in which electron loading at the higher frequencies is small or substantially eliminated.

A further object of my invention is to provide such a tube having low noise characteristics.

The novel features which I believe to be characteristic of my invention are set forth with particularity in the appended claims, but the invention itself will best be understood by reference to the following description taken in connection with the accompanying drawings in which Figures 1 and 2 are diagrams illustrating principles of my invention, Figure 3 is a trans-

verse longitudinal section of one form of an electron discharge device made according to my invention, Figures 4 and 5 are enlarged sectional views of portions of the tube shown in Figure 3 and showing details of construction, Figure 6 is a transverse longitudinal section of a modification of an electron discharge device made according to my invention and Figure 7 is a perspective of details of construction of the tube shown in Figure 6, and Figure 8 is a longitudinal section of a still further modification of my invention.

In order to provide an electron discharge device of the type described and having the characteristics pointed out in the objects of the invention, I utilize, in accordance with my invention narrow dense beams, that is, beams of high current density combined with high deflection sensitivity and secondary emission amplification. Whereas, in conventional beam tubes it is necessary to employ comparatively large currents which make it difficult to provide sharp beams and high deflection sensitivity, by using a multiplier type of tube, smaller currents can be utilized where the initial control is applied to the electron beam, resulting in greater deflection sensitivity. The smaller current in the beam reduces space charge effects permitting a sharp edge beam which with high deflection sensitivity will result in a tube having a high transconductance. If high transconductance is obtained it is possible to reduce the output capacity between the screen and plate by reducing the area of the screen and plate. The input capacity may be made smaller than in conventional type tubes by decreasing the deflecting plate capacity, which in deflection type beam tubes measures the input capacity. I accomplish this by having wider spacing and smaller area for the deflecting plates made possible by smaller initial current. This in combination with properly balanced voltages for reducing the transit time of the electrons past the deflecting electrodes will decrease the input loading of the tube. These various desirable characteristics are obtained by the tubes described below and made according to my invention.

To better understand my invention the theory underlying my invention is discussed below. Consider a sharply focussed rectangular beam deflected past a rectangular aperture in electrode E at the end of a pair of deflecting plates p of length l and spacing d as shown in Figure 1. The transconductance per cm. of length of such a device is equal to the product of the current

density at the aperture A_1 by the deflection sensitivity S . For the simple case shown

$$S = \frac{p}{4dV} \quad (1)$$

thus

$$g_m = \frac{I_0 p}{4dV} \quad (2)$$

where V = average potential on the deflecting plates with respect to the cathode potential. Now it can be shown that there is a theoretical limit to the current density which can be converged into a line focus from any electron source of density I_0 and this limit is given by the expression,

$$I_m = I_0 \left(\frac{2Ve}{\pi KT} \right)^{1/2} \sin \theta \quad (3)$$

where

e = electronic charge

I_0 = current density of source

θ = angle of convergence of the beam

T = temperature of the source

V = energy of the electrons

In the case of the deflection tube the angle θ is small so that $\sin \theta$ is approximately $d/2l$; thus the limiting current density becomes,

$$I_m = I_0 \left(\frac{2Ve}{\pi KT} \right)^{1/2} \frac{d}{2l} \quad (4)$$

Combining (2) and (4) the following expression for the limiting transconductance is obtained,

$$g_m = \frac{I_0}{8} \left(\frac{2e}{\pi KT} \right)^{1/2} \frac{1}{V^{1/2}} \text{ mhos/cm.} \quad (5)$$

Three important facts appear from this expression;

(1) The maximum g_m is independent of deflecting plate spacing which means that the spacing can be made relatively large in order to reduce input capacity.

(2) The g_m depends on the current density of the beam and not on the total current, which indicates that there is theoretically no limit to g_m/I as in conventional tubes.

(3) The g_m is proportional to the transit times (t) through the deflecting plates where

$$t = \frac{1}{5.95 \times 10^7 \sqrt{V}}$$

The expression for g_m can then be written as

$$g_m = .6I_0 \left(\frac{e}{KT} \right)^{1/2} t \times 10^7 \quad (6)$$

From a consideration of the drop of deflection sensitivity with the transit angle through the deflecting plates it can be shown that the optimum transit time through the plates is roughly one half period.

It is difficult to approach this theoretical limit of g_m for a number of reasons including; spreading of the beam by space charge forces, aberrations in the lens system due to space charge and other effects, mechanical alignment of apertures, etc. To minimize these effects I have devised a deflection gun the basic theory of which can be described with reference to the simplified structure shown in Figure 2. The gun consists essentially of an electron source K , a rectangular defining aperture A_1 which is imaged on the final rectangular aperture A_3 by the lens L . V_1 and V_2 are the voltages applied to electrodes having apertures A_1 and A_2 and deflecting electrodes D_1 and D_2 . The width of the aperture is W .

Assuming a perfect lens system a sharp edged image of A_1 can be formed at A_3 by adjusting the ratio of V_1 to V_2 ; and the current density at A_3 will depend on the current density at A_1 and the magnification ratio but not on the size of the aperture.

To obtain a sharp image the lens aberrations must be kept small. This can be done by keeping the total beam current low to reduce space charge effects, and by limiting the beam to a small fraction of the lens opening. The spreading of the beam passing through aperture A_1 is due to three things: (1) space charge forces, (2) lens effect of aperture, (3) radial emission velocities. Now, except for extremely small apertures the most important diverging effect is that due to the lens action of the aperture. Assuming this to be the case and referring to Figure 2 the following approximate relation can be set up for the aperture lens effect,

$$d = K \frac{p}{2} W$$

where K will depend upon what fraction of d is allowed for the spread of the beam. For practical cases, I believe, K can be taken as 2 in which case the beam width is roughly $d/4$ at the second aperture.

In my experimental tubes I have used apertures from .025 to .0025 cm. usually compromising on about .01 cm. I believe that with the smallest apertures I have used that the spreading due to the initial velocities is predominate so further reduction would not be of much value. It is interesting that this size of aperture is also somewhere near the practical mechanical limit.

In Figure 3 the L-shaped exhausted envelope 10 is provided with a cathode 11 for supplying electrons and a beam forming and deflecting arrangement comprising the tubular member 12 which shields the space in which the beam is formed and deflected and which supports the beam forming element 13 provided with limiting aperture 13'. A focusing element 14 forms with the deflecting electrodes 17 and 18 an electron lens for imaging the beam at the aperture 13' in the element 13, in the aperture 16' of the intercepting electrode 16 which assists in the modulation of the beam by electrodes 17 and 18 as will be described below.

Positioned between the apertured elements 13 and 14 may be placed a secondary emission screening electrode 15 which may be used for preventing the return of secondary electrons from the focusing electrode 14 to the aperture 13' in the apertured electrode 13 and thus setting up undesirable interference with the beam.

The details of construction of the beam forming and deflecting electrode, which is the control element, and the lens action is shown in more detail in Figure 4. It will be seen that aperture 13' of the element 13 forms and directs a beam of electrons through the aperture 14' in the element 14, which with the deflecting electrodes 17 and 18 provides an electron lens for focusing the beam on the aperture 16' of the element 16. The electrode 15 filters out electrons which have fanned out between the elements 13 and 14, thus maintaining a sharply defined beam to the electron lens by electrode 14 and deflecting plates 17 and 18. By the action of this lens the electron beam is focused into a sharp dense beam at the aperture 16'.

The deflection sensitivity at low frequency for

the parallel deflection plates is given by the ratio of

$$\frac{l}{4dV}$$

where l is the length of the plates with the aperture at the end of the deflecting plates as shown in Figure 1 and d the spacing between. Hence by making l longer the deflection sensitivity is increased. However, this increases the capacity but by increasing the distance d between the plates the increased capacity can be offset by an increase in spacing. Thus, while the capacity is maintained at a small value the deflection sensitivity is increased.

By means of my invention I obtain a dense beam which is narrow and sharp and in which the deflection sensitivity is high so that the resulting transconductance is also high. The beam after passing through the aperture 16' is directed through the shielding and accelerating electrode 19 provided with aperture 19', the beam being directed to the first secondary emitting surface 20 and in succession to the secondary emitting surfaces 21, 22, 23, and 24 and finally being received by the output electrode 25, these electrodes being maintained at successively higher potentials by the voltage sources 30 and 31 so that the electrons are continuously accelerated toward the output electrode 25.

A voltage source 27 maintains the deflecting electrodes 17 and 18 at a higher positive potential than the cathode while the voltage source 28 maintains the tubular member 12 and elements 13, 14, 15, and 16 at a higher positive potential than the cathode. The input voltage is applied to the deflecting electrodes by means of secondary of input transformer 26, the output being applied to the output circuit 32. By-passing accomplished by condensers 33, 34, 35, 36, and 37, the first three of which are preferably mounted inside the bulb for very high frequency operation.

In operation an electron beam is directed through the beam forming lens system and deflecting arrangement to the secondary emitting surfaces and the output received at the output electrode 25. As pointed out above, due to the increase of sensitivity very small currents can be initially utilized thereby making it possible to more easily control the beam and focus it into a sharp small beam, resulting in a tube having a higher transconductance and a higher ratio of transconductance to current which is a desirable feature. The input capacities are decreased by proper design and spacing of the deflecting electrodes, for example, in a tube made according to my invention 40 mil spacing is used instead of the usual 5 to 10 mil spacing of conventional grid controlled tubes. As pointed out above because smaller output currents are used due to the high g_m/I_p in the tube, a smaller output electrode and screen can be used which thus results in smaller output capacities. Input loading is reduced by reducing the transit time of the electron beam between the deflecting plates by applying proper voltages to these plates and by using plates which are not too long.

In one form of tube constructed according to my invention employing a five-stage electron multiplier arrangement, I obtained a g_m equal to 50,000 μ mhos with only 1 milliampere plate current which is considerably better than conventional tubes. The total input and output capacity was only 7 μ uf.

Another improved form of my invention is shown in Figures 6 and 7 in which a simplified improved gun structure and improved output system is shown. In this arrangement the envelope 40 encloses a cathode 41 and the beam forming and deflecting system comprises a tubular member 42, the limiting apertured electrode 43, the lens element 44, deflecting electrodes 46 and 47 insulatingly supported by glass beads 48 and apertured element 45 for modulation. An element for assisting in the beam formation and electrically connected to the cathode is shown at 49. Shielding electrode 50 is mounted adjacent the end of the beam forming and deflecting arrangement and has an aperture registering with the aperture in the element 45. This element and the electrode 51 electrically connected to it are maintained at cathode potential so that electrons passing through the aperture 20 in the electrode 50 are deflected to the first multiplier electrode 52, the electrons moving to 53 and 54 and output anode 56 as indicated by the dotted lines, output anode 56 being screened by screen electrode 57 lying along an equipotential 25 of the multiplier system. As in connection with the tube described above, the apertured electrode 44 together with the deflecting plates 46 and 47 form a converging lens which is used to image the first aperture 43' in element 43 on the final aperture 45' in the element 45. The size and spacing of the apertures is so proportioned that a sharp image is formed in the final aperture. The length of the deflecting plates may be chosen to obtain the desired maximum sensitivity at the predetermined frequency.

For example, tubes designed for maximum sensitivity at 500 megacycles have a static transconductance (g_m) of 200,000 μ mhos with 15 ma. plate current and a gain of more than 20 to 1 at 40 a frequency at 450 megacycles with a 10 megacycle band width, which is considerably better than present tubes.

A further improvement resides in the output electrode system in which the screen 57 is positioned on an equipotential surface of the multiplier system. A number of leads and supports 58, 59 and 60 are brought out from the screen and the plate through the end of the tube. The construction shown gives good screening and low inductance and allows the leads to be extended, if desired, into a concentric line circuit although in the figures shown the concentric line circuit is not used.

The beam forming and deflecting members of 55 the tube are maintained at a positive potential with respect to cathode 41 by means of voltage source 63 and the deflecting electrodes 46 and 47 had a positive potential different from the rest of the beam forming and deflecting arrangement by voltage source 62. The input voltage is applied to deflecting plates 46 and 47 by inductance 61 which may form the secondary of an input transformer. The secondary emitting elements are maintained at successively higher potentials by means of voltage source 64. By-passing is provided by means of condensers 66, 67, 68, 69, 70, and 71, which though not so shown are preferably mounted inside the bulb for ultra high frequency operation. The output circuit 70 65 is connected to the output anode 66 as shown.

In one specific example of my invention, the cathode was provided with a coated area of .5 x 8 mm. and separated from the first apertured electrode, for example, 43 in Figure 6 a distance of 3 mm., apertured electrodes 44 and 45 being spaced

10 and 25 mm., respectively, in succession from each other. The aperture 43' in electrode 43 was .1 mm. x 5 mm., the aperture in 44 1 mm. x 10 mm. and aperture 45' .25 mm. x 5 mm. The deflecting plates 46 and 47 were 10 x 10 mm. respectively and separated by a spacing of 1 mm. The cylindrical shield 42 and disc members had applied a voltage of 300 volts positive with respect to the cathode and the deflecting electrodes had applied a voltage of about 140 volts. The total current between the plates was approximately 300 milliamperes and through the final aperture 150 ma. giving a maximum g_m of 100 micromhos for the gun structure shown. This tube can be operated successfully up to a frequency of 500 megacycles.

In one form of device made according to my invention and in which the transit time of the electrons is reduced, is shown in Figure 6. In this case the end of the beam forming and deflecting arrangement, which may be referred to as an electron gun, is placed on an equipotential of the multiplier structure and with the proper potential so that electrons are introduced with the velocity they would have if they came from a preceding stage. The advantage of this input system is that the electrons are not slowed down to zero and thus the transit time is small. In the form shown here the envelope 70 contains cathode 71, shield and focusing element 72, the beam forming and deflecting structure comprising tubular member 72 and apertured electrodes 73, 74, and 75, deflecting electrodes 76 and 77 being provided intermediate elements 74 and 75. The element 75 is positioned to lie along an equipotential and the secondary emitting electrode 78 and 80 being positioned to receive the beam, the anode 81 being enclosed and shielded by the screen 82, both being supported by support and lead wires 83, 84, and 85. The voltage sources for properly biasing the various electrodes are indicated at 87, 88, and 89, the input being provided through the secondary of the transformer 86 and output circuit being indicated at 90.

Tubes made according to my invention have shown remarkably improved characteristics, the transconductance being comparatively high and ratio of transconductance to output current being high resulting in the numerous improvements noted above. Because of the improved ratio of transconductance to current, the noise factor is very much improved. The tube results generally in a more efficient tube for use at the ultra high frequency.

While I have indicated the preferred embodiments of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

I claim:

1. An electron discharge device having a source of primary electrons, secondary emitting means for receiving said primary electrons and an electrode for receiving secondary electrons, means positioned between said primary electron source and said secondary emitting means for focusing and controlling the number of primary electrons impacting on the secondary emitting means, said focusing and controlling means for primary elec-

trons comprising a pair of transverse apertured electrodes with the apertures in alignment, deflecting plates positioned between said apertured electrodes and closely adjacent one of said apertured electrodes to provide an electron lens for providing a sharply imaged beam at the aperture of the apertured electrode nearest the secondary emitting means.

2. An electron discharge device having a source of primary electrons, secondary emitting means for receiving said primary electrons and an electrode for receiving secondary electrons, means positioned between said primary electron source and said secondary emitting means for focusing and controlling the number of primary electrons impacting on the secondary emitting means, said focusing and controlling means for primary electrons comprising a tubular member supporting a pair of transverse apertured elements with the apertures in alignment, deflecting plates positioned between said apertured elements and closely adjacent one of said apertured elements forming with said one apertured element an electron lens for providing a sharply imaged beam at the aperture of said apertured element nearest the secondary emitting means.

3. An electron discharge device having a source of primary electrons, secondary emitting means for receiving said primary electrons and an electrode for receiving secondary electrons, means positioned between said source of primary electrons and said secondary emitting means and comprising a tubular member having a plurality of apertured electrodes positioned successively along its length and having the apertures aligned between the cathode and the secondary emitting means, a pair of deflecting electrodes positioned between two of said apertured electrodes adjacent the secondary emitting means and being closer to the apertured element farthest removed from said secondary emitting means for providing an electron lens for forming a sharply focused electron beam passing through the apertured electrodes to said secondary emitting means.

4. An electron discharge device having a source of primary electrons, secondary emitting means for receiving said primary electrons and an electrode for receiving secondary electrons, means positioned between said source of primary electrons and said secondary emitting means and comprising a tubular member having a plurality of apertured elements positioned successively along its length and having the apertures aligned between the source of primary electrons and the secondary emitting means, a pair of deflecting electrodes positioned between two of said apertured elements adjacent the secondary emitting means and being closer to the apertured element farthest removed from said secondary emitting means for providing an electron lens for forming a sharply focused electron beam passing through the apertured elements to said secondary emitting means, and a shielding and accelerating element positioned between the secondary emitting means and said last apertured electrode.

5. An electron discharge device having a source of primary electrons, secondary emitting means for receiving said primary electrons, means positioned between said primary electron source and said secondary emitting means for focusing and controlling the number of primary electrons impacting on the secondary emitting means, said focusing and controlling means for primary electrons comprising a tubular member supporting a pair of transverse apertured elements with the

apertures in alignment, deflecting plates positioned between said apertured elements and closely adjacent one of said apertured elements and forming with one of said apertured elements an electron lens for providing a sharply imaged beam at the aperture of said one of said apertured elements closest said secondary emitting means, an output anode positioned to receive the secondary electrons and having a surface inclined to the path of the electrons and a screened electrode positioned adjacent the anode and lying along an equipotential of said anode.

6. An electron discharge device having a source of primary electrons, secondary emitting means for receiving said primary electrons, means positioned between said primary electron source and said secondary emitting means for focusing and controlling the number of primary electrons impacting on the secondary emitting means, said focusing and controlling means for primary electrons comprising a tubular member supporting a pair of transverse apertured elements with the apertures in alignment, deflecting plates positioned between said apertured elements and closely adjacent one of said apertured elements and forming with said apertured element an electron lens for providing a sharply imaged beam at the aperture of the other apertured element, an output anode positioned to receive the secondary electrons and having a surface inclined to the path of the electrons and a screened electrode positioned adjacent the anode, and lead and support wires extending through one end of the envelope and supporting said screen and anode.

7. An electron discharge device having a source of primary electrons, secondary emitting surfaces for receiving said electrons for releasing secondary electrons when impacted by said primary electrons, and an anode for receiving the secondary electrons, a beam forming and deflecting mount positioned between the cathode and the secondary emitting surfaces and comprising an elongated tubular electrode surrounding the path of the electrons from the cathode to the secondary emitting surfaces and provided with a plurality of transverse apertured electrodes, a pair of beam deflecting plates adjacent one of said apertured electrodes and providing therewith an electron lens, shield electrodes positioned at opposite ends of said beam forming and deflecting mount to be maintained at a potential not greater than that of the cathode potential and a deflecting electrode electrically connected to the shielding electrode adjacent the secondary emitting electrode whereby the beam of electrons emerging from the beam forming and deflecting mount will be deflected toward the surface of the secondary emitting elements, said anode being of triangular cross section and a screen positioned between it and the secondary emitting means and lying along an equipotential of the anode established during operation of the tube.

8. An electron discharge device having a source of primary electrons, secondary emitting means for receiving said primary electrons, means positioned between said primary electron source and said secondary emitting means for focusing the electrons into a beam and controlling the number of primary electrons impacting on the secondary emitting means, and including an electron lens and an apertured element, and means between the lens and the apertured element for deflecting the focused beam across the aperture in the apertured element, and an anode for receiving the secondary electrons, and a shield having a for-

5 inous screen in the path of the secondary electrons and completely enclosing said anode, the apertured element in said beam forming and deflecting means lying along an equipotential surface adjacent the secondary emitting surface whereby the electron beam passing therethrough impinges on the secondary emitting surface without deceleration.

9. An electron discharge device having a cathode for providing electrons, an electrode for receiving said electrons, means positioned between the cathode and said electrode for receiving the electrons, said means for focusing and controlling the number of electrons impacting on the receiving electrode, said focusing and controlling means comprising a tubular member supporting a pair of transverse apertured elements with the apertures in alignment, deflecting plates positioned between said apertured elements and adjacent one of said apertured elements to form with said apertured element an electron lens for forming a sharply focused electron beam at the aperture nearest the electron receiving electrode.

10. An electron discharge device having a cathode for providing electrons, an electrode for receiving said electrons, means positioned between the cathode and said electrode for receiving the electrons, said means for focusing and controlling the number of electrons impacting on the receiving electrode, said focusing and controlling means comprising a hollow conductive member supporting a pair of transverse apertured elements with the apertures in alignment with each other, deflecting plates positioned between said apertured elements and adjacent one of said apertured elements to form with said apertured element an electron lens for forming a sharply focussed electron beam at the aperture nearest the electron receiving electrode, the length of the deflecting plates being substantially equal to the distance traveled by an electron in one half the period of the voltage applied to said deflecting plates during operation of the electron discharge device.

11. An electron discharge device having a cathode for providing electrons and means for receiving said electrons, means positioned between the cathode and the electron receiving means and comprising a tubular member having a plurality of apertured elements positioned successively along its length and having the apertures aligned between the cathode and the electron receiving means, a pair of deflecting electrodes positioned between two apertured elements adjacent the electron receiving means and being closer to the apertured element farthest removed from the electron receiving means for providing an electron lens for forming a sharply focussed electron beam passing through the apertured element nearer the electron receiving means.

12. An electron discharge device having a cathode for providing electrons and means for receiving said electrons, means positioned between the cathode and the electron receiving means and comprising a tubular member having a plurality of apertured elements positioned successively along its length and having the apertures aligned with each other between the cathode and the electron receiving means, a pair of deflecting electrodes positioned between two apertured elements adjacent the electron receiving means and being closer to the apertured element farthest removed from the electron receiving means for providing an electron lens for forming a sharply focussed electron beam passing through the apertured element nearer the electron receiving

means, the length of the deflecting electrodes being substantially equal to the distance traveled by an electron in one half the period of the voltage applied to said deflecting electrodes during operation of the electron discharge device.

13. An electron discharge device having a source of electrons, means for receiving said electrons, means positioned between the source of electrons and the electron receiving means and comprising a tubular member having a plurality of apertured elements positioned successively along its length and having the apertures aligned between the cathode and the electron receiving means, a pair of deflecting electrodes positioned between the two apertured elements adjacent the electron receiving means and being closer to the apertured element farthest removed from the electron receiving means for providing an electron lens for forming a sharply focussed electron beam passing through the apertured element nearer to the electron receiving means.

14. An electron discharge device having a source of electrons, means for receiving said electrons, means positioned between the source of electrons and the electron receiving means and comprising a tubular member having a plurality of apertured elements positioned successively along its length and having the apertures aligned between the cathode and the electron receiving means, a pair of deflecting electrodes positioned between the two apertured elements adjacent the electron re-

- ceiving means and being closer to the apertured element farthest removed from the electron receiving means for providing an electron lens for forming a sharply focussed electron beam passing through the apertured element nearer to the electron receiving means, and a shielding and accelerating electrode positioned between the electron receiving means and said last apertured element.
- 10 15. An electron discharge device having a source of electrons, means for receiving said electrons, means positioned between the source of electrons and the electron receiving means and comprising a tubular member having a plurality of apertured elements positioned successively along its length and having the apertures aligned with each other between the cathode and the electron receiving means, a pair of deflecting electrodes positioned between the two apertured elements adjacent the electron receiving means and being closer to the apertured element farthest removed from the electron receiving means for providing an electron lens for forming a sharply focussed electron beam passing through the apertured element nearer to the electron receiving means, the length of the deflecting electrodes being substantially equal to the distance traveled by an electron in one half the period of the voltage applied to said deflecting electrodes during operation of the electron discharge device.

GEORGE ROSS KILGORE.
